Term of patent 14 years

(Cl. D74—1)

FIG. 1

FIG. 3

Fig. 1 is a front perspective view of a combined desk set and calendar, showing my new design, the back thereof being plain and unornamented;

Fig. 2 is a top plan view; and

Fig. 3 is a side perspective view thereof.

The essential features of my design reside in the portions shown in solid lines on the drawing.

I claim:

The ornamental design for a combined desk set and calendar, substantially as shown and described.
